Devine, Inc., Kansas City, Mo., a corporation of Missouri

Application May 22, 1939, Serial No. 85,115

Term of patent 7 years

To all whom it may concern:

Be it known that we, Marion A. Summerour and Harry C. Devine, Jr., citizens of the United States, both residing at Kansas City, in the county of Jackson and State of Missouri, have invented a new, original, and ornamental Design for a Lighting Fixture, of which the following is a specification, reference being had to the accompanying drawing, forming a part thereof.

Fig. 1 is a front elevational view of the lighting fixture, showing our new design;

Fig. 2 is a side elevational view thereof; and
Fig. 3 is top plan view thereof.

We claim:

The ornamental design for a lighting fixture, as shown.
